UNITED STATES PATENT OFFICE.

ED C. BOWEN, OF BOTTINEAU, NORTH DAKOTA.

INTERNAL-COMBUSTION ENGINE.

1,161,833.

Specification of Letters Patent. Patented Nov. 30, 1915.

Application filed March 13, 1915. Serial No. 14,222.

To all whom it may concern:

Be it known that I, ED C. BOWEN, a citizen of the United States, residing at Bottineau, in the county of Bottineau and State 5 of North Dakota, have invented certain new and useful Improvements in Internal-Combustion Engines, of which the following is a specification, reference being had to the accompanying drawings.

10 This invention relates to certain improvements in internal combustion engines; and it is an object of my invention to provide a device of this general character having novel and improved means including a sleeve rotatably supported within a piston for controlling the operation of the motor.

It is also an object of my invention to provide a device of this general character wherein the controlling sleeve or valve is capable 20 of independent axial adjustment within the cylinder and wherein the piston is mounted for reciprocation within the sleeve or barrel.

Furthermore, it is an object of my invention to provide a device of this general character 25 wherein the reciprocating piston is capable of free axial rotation so that the piston will offer no resistance to the requisite axial adjustment of the rotary valve or sleeve.

30 It is a still further object of my invention to provide a device of this general character including novel and improved means whereby the rotatable sleeve or valve may be maintained in operative position.

35 The invention consists in the details of construction and in the combination and arrangement of the several parts of my improved internal combustion engine whereby certain important advantages are attained 40 and the device is rendered simpler, less expensive and otherwise more convenient and advantageous for use, all as will be herein after more fully set forth.

The novel features of the invention will 45 be carefully defined in the appended claim.

In order that my invention may be the better understood, I will now proceed to describe the same with reference to the accompanying drawings, wherein—

50 Figure 1 is a vertical sectional view illustrating an internal combustion engine constructed in accordance with an embodiment of my invention; Fig. 2 is a sectional view taken substantially on the line 2—2 of Fig.

55 Fig. 1; Fig. 3 is a sectional view taken substantially on the line 3—3 of Fig. 1; and Fig. 4

is an elevational view, detached, and on a reduced scale, of the sleeve herein embodied.

As disclosed in the accompanying drawings, C denotes a cylinder operatively supported by the frame F and having its end adjacent the frame open, said frame being provided with the opening 1 in register with the bore of the cylinder C. The wall of the opening 1 is provided with an annular groove 2 adapted to receive an outstanding annular flange 3 formed on the lower or projected extremity of the sleeve or valve member 4, said valve member or sleeve having its inner extremity closed by the head 5, 60 said sleeve or valve member being adapted to snugly fit within the cylinder C and capable of axial rotation therein.

The head 6 of the cylinder C at its axial center is provided with the threaded opening 7 with which the spark plug 8 is adapted to be engaged, said spark plug having its lower extremity disposed through an opening 9 produced at the axial center of the head 50 of the sleeve or valve member 4, said 75 plug is also provided with an annular flange 9' adapted to underlie the head 5 whereby it will be perceived that the plug 8 also serves as a medium for maintaining the valve member or sleeve 4 in applied position.

80 Mounted for reciprocatory movement within the valve member or sleeve 4 is the piston P of conventional construction and having swiveled thereto, as at 10, the inner 85 extremity of the rod 11, the outer or opposite extremity whereof being operatively engaged with the crank shaft 12 supported in any desired manner by the frame F.

85 As herein embodied, the swivel connection 95 between the rod 11 and the piston P is in the form of a conventional ball socket joint, whereby it will be perceived that the piston P will be capable of axial rotation whereby it will offer no obstruction to the axial rotation of the valve member or sleeve 4.

90 As herein disclosed, the valve member or sleeve 4 projects through the opening 1 and is provided with the annular gear member 14 in mesh with the diametrically opposed 105 worms 15 affixed to the parallel shafts 16 suitably supported by the frame F whereby it will be perceived that upon imparting axial rotation to the shafts 16, the valve member or sleeve 4 will be caused to rotate. 110

In the present embodiment of my invention, the crank shaft 12 is provided with a

sprocket 17 around which is disposed the chain 18 also directed around the sprockets 19 affixed to the parallel shafts 16 whereby it will be perceived that the rotation of the 5 shaft 12 under the influence of the piston P will result in the desired axial rotation of the shafts 16 and more particularly of the valve member or sleeve 4.

20 denotes an intake port in communication with the interior of the cylinder adjacent the inner end thereof and 21 denotes an exhaust port, said ports 20 and 21 being relatively positioned at an angle of 146.25 degrees and are adapted to register with the 10 ports 22 produced in the valve member or sleeve 4 adjacent the inner end thereof, said ports 22 being positioned at angles of 180 degrees and herein set forth as two in number, the ports 20 and 21 and 22 are elongated 15 annularly of the cylinder C and valve member or sleeve 4 and are preferably of a length equal to 11.25 degrees.

With the crank shaft 12 in vertical dead center, a port 22 is positioned 11.25 degrees 25 in advance of the intake port 21. The valve member or sleeve 4 and the crank shaft 12 actually rotate in a ratio of 1 to 4. Therefore, when the crank shaft has rotated 180 degrees, the sleeve has traveled 45 degrees, 30 and the port 22 of the sleeve has passed the intake port 20 and closed such port. On the upward stroke of the piston or compression cycle, the shaft 12 travels 180 degrees, making one complete revolution when the 35 port 22 is 90 degrees past starting point. At this time the spark plug 8 is intended to ignite the compressed gases, driving the piston P outward and rotating the crank shaft 12 180 degrees and the sleeve or valve member 40 45 degrees, at which time the port 22 is just communicating with the exhaust port, and as the piston P travels its fourth cycle and the crank shaft 180 degrees, the burned gases are expelled through the exhaust 45 port 21.

It will now be observed that the following port 22 is 11.25 degrees before the intake port 20 so that while the crank shaft 12 travels 45 degrees before the second mentioned port 22 communicates with the intake port 20, a vacuum will be produced in the cylinder above the piston P so that when the second named port 22 does communicate with the port 20 the explosive mixture will 50 be drawn into the cylinder. The ignition system coacting with the spark plug 8 may be as preferred and a detail thereof is believed to be unnecessary.

The periphery of the valve member or

sleeve 4 and the outer face of the head 5 60 thereof are provided with the spiral grooves 23 adapted to receive and spread the lubricant delivered through the ports 24 leading from a suitable source of supply.

From the foregoing description, it is 65 thought to be obvious that an internal combustion engine constructed in accordance with my invention is of an extremely simple and comparatively inexpensive nature and is particularly well adapted for use by 70 reason of the convenience and facility with which it may be assembled, and it will also be obvious that my invention is susceptible of some change and modification within the 75 scope of the appended claim without material departure from the principles and spirit thereof and for this reason I do not wish to be understood as limiting myself to the precise arrangement and formation of the several parts herein shown in carrying out 80 my invention in practice.

I claim:

A device of the character described comprising a frame, a cylinder mounted thereon and having an open end adjacent the 85 frame, said frame being provided with an opening in register with the bore of the cylinder, a sleeve positioned within the cylinder and capable of axial rotation, said sleeve projecting within the opening of the 90 frame, an annular flange carried by the sleeve, the wall of the opening of the frame being provided with an annular groove to receive said flange, said cylinder being provided with an intake port and an exhaust 95 port and said sleeve being provided with ports adapted to register with the ports of the cylinder, a piston mounted for reciprocatory movement within the sleeve, said piston being capable of independent axial rotation, an annular gear member secured to the sleeve below the annular flange, parallel shafts disposed at opposite sides of the sleeve and operatively engaged with the annular gear of the sleeve, a crank shaft, an 100 operative connection between the piston and the crank shaft, and a member operatively engaged with the crank shaft and the parallel shafts whereby said parallel shafts are caused to rotate under the influence of the 110 crank shaft.

In testimony whereof I hereunto affix my signature in the presence of two witnesses.

ED C. BOWEN.
